While the 118th Congress is still in session, the House has passed a bill to expand the National Park Service's authority to regulate commercial activities in national parks. The bill, introduced by Rep. Earl Blumenauer, D-Ore., would allow the National Park Service to regulate commercial activities in national parks, such as concession contracts, to ensure that they are consistent with the park's mission and values. The bill has been referred to the House Committee on Natural Resources.

UNITED STATES PATENT OFFICE

2,512,478

VACUUM BREAKER VALVE

Modesto Callejo, New York, N. Y.

Application March 19, 1947, Serial No. 735,761

5 Claims. (Cl. 277—21)

1

The present invention relates to vacuum breaker valves, also known as "back flow preventers," and, more particularly, to a vacuum breaker valve of improved construction which embodies a novel means for controlling fluid flow.

In accordance with the invention the improved vacuum breaker valve is provided with a fluid flow controlling means having two parts which are relatively movable. An important advantage of this novel construction is that leakage of liquid is prevented, while flow of a second fluid, air, for example is completely controlled. The improved valve of this invention may be installed, therefore, in any location without providing for liquid drainage.

An object of the invention is to provide an improved valve for the indicated purpose having fluid flow controlling means of novel design.

Another object of the invention is to provide a novel slide valve in a vacuum breaker valve.

A further object is to provide a vacuum breaker valve which is substantially silent in operation.

Other and more specific objects of the invention will become apparent and suggest themselves to those skilled in the art to which the invention is directed upon reading the following specification and claims in connection with the drawings in which:

Fig. 1 is a diagrammatic view of a typical system in simplified form in which the device of this invention is to be used;

Fig. 2 is a vertical section through a vacuum breaker valve embodying the invention in one form, certain of the parts being in the position assumed when the inlet of the structure is closed;

Figs. 3 and 4 are views similar to Fig. 2, but showing the fluid flow controlling means in different positions assumed during operation of the device:

Fig. 5 is a transverse section on line 5-5 of Fig. 2; and

Fig. 6 is a view similar to Fig. 2, but showing a modification.

Referring to the drawing, and for the present to Fig. 1, there is shown a simplified water distribution system in which a plurality of fixtures, such as a drinking fountain 12 and a tank 14 are located for example on different floors of a building. The water supply for these fixtures is provided by a main riser pipe 16 connected to a suitable source (not shown) from which the water supply is controlled by a master valve 17. The supply for the lower fixture 12 is conveyed through a pipe 21 in the customary manner. For the tank 14 there is provided a branch pipe 22

for providing flow from the riser 16 to the inlet 26 to the tank. The inlet to the tank 14 is shown as being below the level of the liquid 15 in the tank.

5 In the use of a fixture, such as is shown at 14, there is a possibility of waste water such as the liquid 15, being siphoned from the fixture into the riser 16 when a temporary vacuum occurs in the latter, with the undesirable result that such

10 waste water may be subsequently conveyed to other fixtures in the system. In order to avoid this contingency, a vacuum breaker valve structure 28 is interposed between the fixture 14 and the riser 16. The operation of the vacuum breaker is such that when its fluid flow controlling means is operated by pressure of the water in the riser 16 a free flow is permitted to connected fixtures, for example, the fixture 14. However, when the supply is shut off, or a vacuum occurs

15 in the riser, the fluid flow controlling means will operate to close communication between the fixture and the riser so as to eliminate any possibility of waste water in the fixture being siphoned back into the riser.

20 25 The illustrative embodiment of the improved valve of this invention, shown by the drawings is generally similar to the vacuum breaker valve disclosed and claimed in United States Patent No. 2,209,189, granted to the present inventor July 23, 1940. Referring for the present to Figs. 2 and 5 of the drawings, the vacuum breaker 28 is seen to comprise a body made of principal sections 31 and 32 joined for convenience in assembly of the parts by a screw threaded connection

30 35 40 45 34 made fluidtight in any desired manner. The part 31 is flattened or given a hexagonal shape in cross-section at 36 to provide a wrench connection and is threaded at its lower end 38 for coupling to an inlet connection such, for example, as the riser 16 in Fig. 1. A valve seat 39 is provided at the inner end of the inlet 41 adapted for engagement with a cooperating inclined surface 43 on the fluid flow control means 44 of the invention, later to be described in detail. This engagement occurs when there is no fluid pressure in the inlet or when a temporary vacuum occurs in the riser 16.

The part 32 is provided with an internally threaded outlet 46 to receive a conduit for connection with a desired fixture. An opening 47 provides communication with the atmosphere in operation of the device.

The outlet 46 and the opening 47 are in direct communication when the means 44 is in the position of Fig. 2. When the means 44 is

subjected to pressure from the inlet 41, communication between the opening 47 and the outlet 46 is cut off. Screw threads 48 provide for connection of an air pipe or other fitting. For example in Fig. 1, elbows 51 and 52 and a nipple 53 provide for an air inlet which opens downwardly.

A valve chamber 56 accommodates the previously mentioned means 44 which are slidable on bearing guides in the form of projections or elongated fins 58 formed in the inner wall of the valve chamber 56. Three of these fins are present in the illustrative embodiment, but more may be formed in the wall of the part 32 which provides the valve chamber. Three ports 61 are provided, in effect, in the illustrated arrangement.

The fluid control means 44 is a two part slide valve comprising a plunger 63 and a piston 64 telescoping with a sliding fit. Fig. 6 of the drawings, to be described hereinafter, shows a reversal of parts. The plunger 63 is provided with the previously mentioned valve surface 43 which seats on the valve seat 39 on the part 31. The valve seat is flared at 65 where it joins the inner surface of the inlet 41 to assist the fluid flow in raising the plunger 63. The tubular body 66 of the plunger is of such a length that there is some appreciable clearance between the shoulder 68 and the end of the tubular body 71 of the piston. This clearance may be small and is illustrated in the drawing. The upper end of the piston is provided with a small opening 72 to release any fluid such as air or water thereby to eliminate any resistance to the drop of the piston to the position shown in Fig. 2. The upper edge 73 of the tubular body 66 of the plunger is preferably rounded to provide a better seal. The opening 72 may be omitted if the parts 63 and 64 have a very loose fit, but this is not preferred.

The upper end of the piston 64 is provided with a closing disk 74 of yieldable material, such as fiber or rubber. In fact, the disc 74 may be the same as the usual "faucet washer" and it is held in position by suitable means such as a screw. The disc 74 seats against the circular valve seat 78 so as to close communication with the air inlet 47 when pressure exists in the main riser 16.

From the foregoing description of the valve 28 of the invention taken in connection with explanation of the simplified distribution system of Fig. 1 it is believed that its operation will be fully understood. However, to review the operation briefly the piston 64 moves to close the air inlet 47, also called the surge outlet, before the plunger separates from the seat 39. This closing operation is caused either by air or liquid pressure. Vacuum breakers heretofore known leak at the air inlet 47 at a certain critical flow. In accordance with the invention this leakage is eliminated due to the closing of the piston 64 against the valve seat 78 before the plunger 63 leaves the valve seat 39. Fig. 3 of the drawing illustrates this position of the parts. Fig. 4 of the drawing shows the position of the parts when water, for example, in the distribution system of Fig. 1 is flowing into the tank 14.

Fig. 6 of the drawing shows a modification in which the piston 64a slides within the plunger 63a. The piston and plunger 64a and 63a of Fig. 6 are interchangeable in the valve 28 of Figs. 2 to 5 and it will be understood that the inclined valve surface 43a cooperates with the valve seat 39. A closing disc 74a cooperates with the valve seat 78. An air hole 72a performs the same function as the air hole 72 in the modification of the fluid flow control means of Figs. 2 to 5. The upper edge 81 of the tubular body 83 of the plunger 63a is preferably rounded and seats against a flange 86 in the position of the parts corresponding to Fig. 2 or Fig. 4.

What is claimed is:

1. A vacuum breaker valve comprising a valve body having a valve chamber, a two part slide valve in said chamber, a fluid inlet opening to said chamber, one of said parts having means to close said fluid inlet opening, a fluid outlet opening in communication with said valve chamber at all times, an atmospheric opening to said valve chamber, the other of said parts having means to close said opening, and means to relieve fluid pressure in said other part, said last named means being a wall of said other part having an opening.

2. Fluid control means for a vacuum breaker valve comprising a plunger having a valve surface, a tubular extension for said plunger, a piston having valve means for cooperation with a valve seat, and having a tubular body, the tubular extension of said plunger and the tubular body of said piston having relative telescopic movement in operation of said fluid flow control means, the end of said plunger cooperating with a surface on said piston to stop the flow of fluid when said plunger and piston are fully telescoped.

3. The fluid flow control means of claim 2 in which the tubular body of said piston is provided with a fluid escape opening.

4. The fluid flow control means of claim 2 in which said tubular extension of said plunger is slidable within the tubular body of said piston.

5. Fluid control means for a vacuum breaker valve comprising a plunger, a tubular extension for said plunger, a piston having a tubular body, the tubular extension of said plunger being slidable within the tubular body of said piston, and the end of said plunger cooperating with a surface on said piston to stop the flow of fluid when said plunger and piston are fully telescoped.
